EXPLOSIVES PACKAGING

Joseph A. Grow, Jr., Glendale, Mo., assignor to Atlas Powder Company, Wilmington, Del., a corporation of Delaware

Filed July 25, 1957, Ser. No. 674,102

1 Claim. (Cl. 86—1)

My invention consists in a novel method of encasing an explosive body in metal foil.

More specifically my invention comprises the packaging of an explosive pellet in metal for use in ammunition. The novel packaging of lead and booster pellets of the present invention provides an inexpensive but effective package for pellets of explosive material thus eliminating dusting, cracking and chipping during subsequent handling operations.

In ammunition loading it is common practice to compress explosives into pellet form for ease in handling in the loading area. During the handling of the explosive pellets between the powder preparing area and the loading area, it is difficult to avoid chipping, cracking, flaking or dusting. The chips and powder accompanying the pellets present both an explosion and health hazard. It is therefore an object of the present invention to reduce the aforesaid explosion and health hazards.

Also in the loading of explosive components into ammunition it is difficult to prevent explosive dust from becoming lodged on metal parts of the ammunition assembly and when the deposits are on surfaces which are mated with other surfaces there is present the danger of accidental explosion during the assembly operation. This is particularly true if the mating surfaces are to be screwed or crimped together. It is therefore, an object of the present invention to provide an explosive pellet with which the danger of accidental explosion during the assembly of the component parts of military projectiles is minimized.

It is well known that some explosive materials are toxic to certain individuals and may cause dermatitis upon contact with the skin. The present invention of encasing explosive pellets in metal produces pellets which are not subject to flaking, chipping and powdering, thus the danger of explosive material contacting the skin of personnel handling the explosive is largely eliminated. It is therefore an object of the present invention to provide a package which prevents dermatitis due to the handling of explosive material by personnel assembling ammunition components.

Another undesirable consequence of the necessary handling of explosive pellets is that each chip and particle removed from the pellet subtracts from the amount of explosive loaded into the ammunition. While in some instances the loss of explosive due to chipping, etc., may not be significant, the loss may be critical in lead or detonator elements. If a booster pellet significantly reduced in size due to chipping, dusting, etc., is loaded into a fuse it could result in a low order detonation or malfunction when the lead is fired. It is therefore an object of the present invention to provide a pellet with which the aforesaid malfunctions which are the result of an insufficient amount of explosive in the lead detonator or booster charge of an explosive train are largely eliminated. Pellets encased in metal as hereinafter described can be loaded into fuses, boosters or projectiles with little or no danger of lost powder lodging in parts or

2

on individuals performing the assembly operations; moreover there is little likelihood of malfunctioning of the explosive train because of insufficient powder in the lead booster or detonator element.

5 The present invention is a method of encasing an explosive body in metal sheet which comprises forcing said metal through a forming die conforming substantially to the shape of said explosive body, the explosive body serving as a male member of the die assembly. Thereby 10 the metal encases a desired portion of the explosive body and takes the shape of said body.

In the drawings:

Figure 1 is a diagrammatic cross-section of a die assembly showing an explosive pellet and thin sheet of metal prior to blanking and forming.

Figure 2 is a diagrammatic cross-section of a die assembly showing the blanking operation.

20 Figure 3 is a diagrammatic cross-section of a die assembly showing the forming operation with the metal wrap- 20 per being cold drawn about the explosive pellet.

Figure 4 is a diagrammatic cross-section of a die assembly showing the completed forming operation with the punching member and explosive pellet in their most downward position.

25 Figure 5 is a cross-section showing a lead cup and booster cup containing their respective explosive pellets as finally assembled.

Referring to the series of figures, the same reference characters refer throughout to the same parts.

30 Figures 1 to 4 specifically illustrate the application of the present invention to the packaging of an explosive booster pellet 10 which may, for example, be pressed tetryl. The die assembly 7 includes a double-action die comprising a punching member 14 and a blanking mem- 35 ber 15 operating on a cutting matrix 8 and a forming matrix 12. A thin sheet of metal 6, for example, aluminum sheet of 0.01 inch thickness, supports the explosive pellet 10 between the punching member 14 and the female portion of the die assembly 7 as shown in Fig- 40 ure 1.

In Figure 2 the position of the die assembly 7 is shown after the blanking member 15 has moved to its most downward position after having blanked the metal sheet 6. The punching member 14 and the explosive pellet 10 are moved downwardly with the blanking mem- 45 ber 15. The arrows in the various figures indicate the motion of the parts.

Figure 3 shows the punching member 14 moving down- 50 wardly. The metal sheet 6 forms about the explosive pellet 10 which acts as the male member of the die assembly as it is forced into the perforation 16 of the forming matrix 12.

Figure 4 shows the punching member 14 and the explosive pellet 10 in its most downward position with the metal sheet 6 cold drawn about and completely envelop- 55 ing the bottom and side surfaces of the explosive pellet 10. After completion of the forming operation the pellet and its encasing cup are removed from the die for capping and subsequent assembly into the ammu- 60 nition.

The assembled lead cup and booster cup containing the explosive pellets can be readily handled and incorpo- 65 rated into the ammunition as desired.

The specific embodiment of the present invention shown in Figures 1 through 4 have described the pack- 70 aging of an explosive pellet to be used as a booster element of an explosive train in a military projectile. Similar techniques and apparatus can be applied to the pack- aging of a lead explosive pellet, and Figure 5 shows simi- 75 larly fabricated lead and booster pellets combined into one unit as by crimping to form a single metal unit.

As shown in Figure 5 a metal cap 6' has been drawn

about lead pellet 10' by methods such as just described and the lead element is crimped to the top of booster pellet 10 after it has had metal 6 drawn about it. The fabrication of units as described will reduce the hazards hereinabove mentioned and at the same time provide better quality ammunition.

The metal used for drawing about explosive pellets in accordance with the present invention may be of any gauge which can be readily worked with the equipment available and the cohesiveness and hardness of the explosive pellets being encased. It should however not be so thin that it is torn in the process of forming and that the operation becomes merely one of wrapping and folding rather than drawing. Gauges between 0.002 and 0.020 inch have been found satisfactory for aluminum. Similar gauges of other metal sheets may be used.

The metal stock may be any which is conveniently drawn. Aluminum, tin, lead and copper are examples of suitable materials.

The explosives may likewise cover a large range. The pellets may be formed of compressed granules or powder or may be cast. Suitable compositions include tetryl, trinitrotoluene, pentaerythritol tetranitrate, amatol and cyclonite, for example.

The present invention has been described as a method of packaging an explosive element using a solid slug or pellet as the draw punch in a cupping operation. On shallow draws such as encasing of the booster element the cup may be drawn from a flat metal blank in one operation as illustrated in the specific embodiment of the present invention. It is however, within the scope of the present invention to perform die operations requiring deeper draws. In performing deep cup draws one or more preliminary draws may be required in which case

the explosive pellet is used only for the final draw with the preliminary drawing dies being of larger diameter than the explosive pellet.

One advantage of the present invention is that it is adaptable to the encasing of a wide variety of shapes as for example, toruses, cones, prisms, and unsymmetrical shapes.

It is also within the purview of the present invention to provide the complete closure of the encased pellet by inserting a cover in the open end of the cup and then crimping or otherwise securing the metal cup over the cover.

Having thus described my invention, what I claim as new and desire to protect by Letters Patent is:

A method of encasing an explosive pellet in sheet metal of from about .002" to about .020" in thickness which comprises placing the explosive pellet in conjunction with the sheet metal adjacent a forming die conforming substantially to the shape of said explosive pellet, passing said explosive pellet in conjunction with the sheet metal through said forming die, said explosive pellet serving as a male member of a die assembly in cooperation with the forming die, and thereby drawing said sheet metal about the surface of said explosive pellet.
